UNITED STATES PATENT OFFICE.

LOUIS J. AUERBACHER, OF NEWARK, NEW JERSEY, ASSIGNOR TO THE FEDERAL SCREEN CORPORATION, OF NEW YORK, N. Y., A CORPORATION OF NEW YORK.

PROCESS OF MAKING PROJECTION-SCREENS.

1,206,287.

Specification of Letters Patent. Patented Nov. 28, 1916.

Application filed April 8, 1915. Serial No. 20,049.

To all whom it may concern:

Be it known that I, LOUIS J. AUERBACHER, a citizen of the United States, residing at Newark, in the county of Essex and State of New Jersey, have invented certain new and useful Improvements in Processes of Making Projection-Screens, of which the following is a specification.

This invention relates to screens for use 10 in displaying pictures by means of a magic lantern or moving picture projecting apparatus, and its novelty consists in the successive steps of the method of making the screen and the resulting novel product.

15 In the accompanying drawing—Figure 1 is a vertical sectional view through the improved screen. Fig. 2 is a face view of a portion of the same.

Screens upon which to display pictures 20 of the kind described are usually so arranged that the source of light impinges upon a miniature representation of the picture intended to be displayed, passes through a suitable lens system, and the rays, 25 condensed or dispersed as the case may be, are then projected against an opaque screen, whence they are reflected to the eyes of the spectators. The screen which is the subject matter of this application is of a different 30 character. It is composed of transparent or semitransparent material and it is intended that the rays of light striking upon the screen shall be transmitted therethrough and thence reach the eyes of the 35 spectators, the light falling upon the screen from the opposite side being more or less refracted, dispersed, or absorbed by the nature of the surface facing the spectators.

The basis of the screen to be made is any 40 suitable reticulated material in the form of a thin sheet, such as woven wire cloth or bolting cloth or the like. This is placed upon a suitable surface such as a flat table and the upper surface is then coated with 45 a film of transparent material. For this purpose, I prefer to employ a solution of acetate cellulose or nitrate cellulose or pyroxylin in a suitable volatile solvent such as acetone or a primary olefin such as is 50 described in Letters Patent of the United States No. 972,953. The solution is preferably applied with a brush, although if sufficiently dilute the solution may be flowed upon the surface of the reticulated material, but this requires considerable skill and

I prefer on that account to make the applications by means of a brush. The solvent is then removed. This may be accomplished by natural evaporation if the ventilation is good, or the screen may be subjected to the action of a current of hot air, or any other means may be employed to remove the volatile vapors coming off from the solvent. After the solvent has been removed, the result is a transparent or semi-transparent tough flexible film firmly adhering to the reticulated material to which it has been applied.

It will be understood that the range of materials which may be employed is considerable, both for the solvent and the thing dissolved, but according to my present knowledge acetate cellulose dissolved in acetone gives good results.

As stated above, in use, this screen is employed as a receiving surface for a projected image but it is interposed between the source of light and the spectator. When the screen is made of one layer of fabric and one layer of film as above described, either the film side or the fabric side may be presented toward the spectator, but I prefer the latter arrangement, as the outside light or daylight seems to be absorbed better when the screen is so arranged.

The above is the simplest method of making the screen in its simplest form. After forming a coating of film on one side of the fabric as above described, I continue further and turn it over and coat its opposite side in precisely the same manner as before, so that the screen will then consist of a sheet of fabric between two sheets of substantially transparent films. In such case there is of course no right or wrong side to it and either 95 may be presented to the spectator.

I may provide a surface adapted to produce a more complete refraction or absorption of the light from the side of the screen to be presented toward the spectator by 100 forming such surface of a sheet of film which shall present an enormous number of concave interruptions of its continuity, so that while it may appear to be substantially continuous, the surface is nevertheless broken 105 up into lenticular parts or portions which serve as refractive media. In the making of a film of this character, I first make a mold of plaster or glass or similar material provided with convexities and concavities so 110

arranged that a plastic material molded thereon or therein will have a surface of the character described. I then flow or brush the film-making material onto such mold 5 and after a suitable thickness has been applied, remove the solvent as before. Before the film has completely dried, I apply the sheet of reticulated material to its upper surface and it adheres thereto, so as to form 10 an integral portion thereof. The result of course is a screen having a rear side of fabric or reticulated material and a front side of refracted interruptions. I may further continue the process by adding an additional 15 sheet of film at the rear of the reticulated material. When made with such a refractive surface, that side should in use be presented toward the spectator.

I claim:
20 1. The art of making a projection screen

which consists in forming upon the surface of a sheet of transparent film-like material a series of refractive optical elements, and attaching to the opposite side of the sheet a sheet of suitable reticulated material.

2. The process of making a projection screen which consists in forming upon the surface of a sheet of transparent film-like material a large number of interruptions of its continuity whereby the refractive power 30 of such surface is promoted, attaching to the opposite surface thereof a sheet of suitable reticulated material, and providing at the back of the latter sheet a second sheet of film.

In testimony whereof I affix my signature in presence of a witness.

LOUIS J. AUERBACHER.

Witness:

ALDA L. MILLER.
